DESIGN FOR A SMOKING STAND

Onnie Mankki, Cleveland, Ohio, assignor to
Smokador Manufacturing Co., Inc., Bloomfield,
N. J., a corporation of Delaware

Application July 17, 1946, Serial No. 131,658

Term of patent 14 years

(Cl. D85—2)

To all whom it may concern:

Be it known that I, Onnie Mankki, a citizen of the United States, residing at Cleveland, in the county of Cuyahoga and State of Ohio, have invented a new, original, and ornamental Design for a Smoking Stand, of which the following is a specification, reference being had to the accompanying drawing, forming part thereof, in which—

Fig. 1 is a view in perspective of a smoking stand showing my new design; and

Fig. 2 is a top plan view of the smoking stand shown in Fig. 1.

I claim:

The ornamental design for a smoking stand, substantially as shown.

ONNIE MANKKI.
